(57) **CLAIM**

The ornamental design for a nest cover, as shown and described.

DESCRIPTION

FIG. 1 is a front, right perspective view from above showing the design of the nest cover;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The nest cover comprises a translucent material.

The broken lines depict environmental subject matter and form no part of the claimed design.
